Attorney

UNITED STATES PATENT OFFICE

HILTON I. COTTEN, OF HAZLEHURST, MISSISSIPPI

AUTOMATIC LIQUID DISTRIBUTOR

Application filed April 25, 1929. Serial No. 358,123.

My present invention has particular reference to the automatic distribution of gasoline from a visible tank. Another object of my invention is to provide a means for distributing gasoline through a gasoline pump controlled by a crank and the combination of co-acting elements in the gasoline tank that will open the escape valve and at the same time will close the intake valve.

Another object of my invention is to provide a device of the class described which may be easily installed in gasoline pumps of the visible type such as now are in general use. Other objects of the invention comprise adjusting means regulatory with the desire and the need of the user; and further, wherein the construction is simple but sturdy, easily and quickly adjusted, firmly sustained when so adjusted and thoroughly adequate for its purpose.

To the attainment of the foregoing, the improvement also resides in other details of construction, combination and operation of parts, one satisfactory embodiment of which is described in the accompanying drawings.

In the drawings

Figure 1 is a cross-sectional side view of a visible gasoline pump with the device installed therein.

Figure 2 is a detailed cross-sectional view of the intake pipe and the control elements in connection therewith.

Figure 3 is a detailed side view of the cam rod and connecting gear.

Referring now to the drawings in detail, the numeral 1 designates the tank into which the gasoline is pumped before distribution. Numeral 2 designates a tube mounted in the base of the tank with an opening extending through the tube downward, and the tube of such a height as to be above the height of the gasoline pumped into the tank 1. Disposed within the tube 2 and adapted to slide therein is a cam shaft 3 which extends downward through the supporting parts of the tank 1, and has disposed on one side of the lower extremity thereof a series of teeth adapted to engage with a tooth gear, such as described in Figure 3.

The upper extremity of the shaft 3 extends into a cap piece 2a disposed above and supported by the tube 2. A slotted opening extending on either side of the tube 2 to the cap 2a permits the extension of the lugs 3b and 3c from the shaft 3 and oppositely disposed to these lugs a valve stop arm and stopper 3d and 3e.

Disposed in one side of the tube 2 are several supporting lugs 2b which maintain the shaft 3 in a relative position with relation to the lugs 3b and 3c. At the lower extremity of the shaft 7 is a stopper element 7b, and at the upper extremity of the shaft 7 is an arm 7a adapted to engage alternately with the lugs 3b and 3c.

Disposed in the base of the tank 1 is the outlet pipe 4 with a mouth 4a adapted to be closed by the stopper 7b.

Preferably there is mounted in the tank a float control valve comprising the cross arm member 6 with the link 6a at one end thereof supporting the float 6b. The opposite extremity of the member 6 has a link 6c disposed in connection therewith and at the extremity thereof is a valve piston 6d adapted to move within the intake pipe 5.

Extending from the gear member 9, which engages the shaft 3 is the crank shaft 10 supported by the tank support proper and extending through the side thereof to the side of the tank support, the crank arm terminating in a crank handle 10a.

The crank may be turned thereby raising the shaft 3. When this is done the lug 3b engages with the arm 7a and raises the valve stopper 7b from the mouth 4a of the escape pipe 4, thus permitting the gasoline in the tank to pass out of the tank. At the same time that the arm 7a is raised by the lug 3b, the arm 3d, with the stopper valve 3e at the extremity thereof, closes the mouth 5a of the intake pipe 5 thus preventing any liquid from passing through the opening 5a into the tank 5. The adjustment of the elements 3e and 7b are such that the mouth 5a is closed momentarily before the mouth 4a is opened.

As a second valve control, to close the mouth 7a, there is preferably employed the float 7b, as heretofore described, which will

fall as the gas is let out of the tank thereby raising the valve 6d into a predetermined position so as to close the mouth 5a of the intake pipe 5.

5 The weight of the shaft 3 will cause it to lower itself by gravity, and in so doing the lug 3c will engage with the arm 7a thereby lowering the valve stopper 7b to close the mouth 4a of the outlet pipe 4, and correspondingly, the arm 3d is lowered, opening the mouth 5a and thereby permitting gasoline to flow into the tank 1. The valve 6d is lowered simultaneously with the lowering of the shaft 3. An overflow pipe is not shown 10 in the drawings, but being a part of the standard equipment governs the height of the gas in the tank.

15 The construction, operation and advantages of my invention will, it is believed, be understood and appreciated by those skilled in the art when the foregoing description has been read in connection with the accompanying drawings. The degree of adjustment of the several members in relation to each other 20 is such as to take care of any requirements; and while I have here shown and described and pointed out certain novel features of my invention, it is understood that various omissions, substitutions and changes in the form 25 and detail of the device illustrated and its means of operation may be made by those skilled in the art, and that I do not wish to be restricted to the structure disclosed, but hold myself entitled to make such changes 30 therefrom as fairly fall within the scope of what I claim.

35 What I claim is:

1. In a device of the class described, a cam shaft adapted to move longitudinally 40 within a gasoline tank and in conjunction with said shaft, means to manually open and close an outlet pipe controlled by the lateral movement of the shaft, the movement of the shaft responsive to elevating and lowering 45 the means.

2. In a device of the class described, a vertically disposed shaft responsive to actuating mechanism adapted to move in a vertical position within a tank, and in conjunction with 50 said shaft, means to open and close the opening in an inlet pipe, said means responsive to the vertical movement of the shaft.

55 3. In a device of the class described, a vertically disposed shaft responsive to an actuating means and adapted to vertical movement within a fluid container and in conjunction with said shaft associated means to automatically open or close the mouth of the outlet pipe and a secondary associated means 60 adapted to simultaneously close or open the mouth of an inlet pipe.

In testimony whereof I hereunto affix my signature.
